(57) **CLAIM**

The ornamental design for a lid for jar as shown and described.

DESCRIPTION

1. Lid for jar

1.1 : Perspective

1.2 : Front

1.3 : Back

1.4 : Left

1.5 : Right

1.6 : Top

1.7 : Bottom

1.8 : Reference view showing status in use

This design provides a sealing lid of the container which is roughly rectangular with arc-shaped decorations at the four corners and has two U-shaped flanges protruding upward from the left and right edges of the top surface; There's a long groove on the top surface of the lid, and a long handle is stored and pivoted inside the long groove; Figure 1.8 is showing status in lifting up the long handle; The broken lines shown represent unclaimed subject matter and form no part of the claimed design; The characteristic features of the design lie in the shape as shown.
